UNITED STATES PATENT OFFICE.

THOMAS SPENCER, OF PHILADELPHIA, PENNSYLVANIA, ASSIGNOR TO HELIOS UPTON COMPANY, OF PHILADELPHIA, PENNSYLVANIA, A CORPORATION OF NEW JERSEY.

REGULATOR FOR ELECTRIC CURRENTS.

SPECIFICATION forming part of Letters Patent No. 728,034, dated May 12, 1903.

Application filed December 16, 1901. Serial No. 86,026. (No model.)

To all whom it may concern:

Be it known that I, THOMAS SPENCER, of Philadelphia, in the State of Pennsylvania, have invented certain new and useful Improvements in Regulators for Electric Currents, whereof the following is a specification, reference being had to the accompanying drawings.

My invention relates to that class of regulators wherein a solenoid-coil is included in the circuit to be regulated, in such relation with an iron core that relative movement of the solenoid and core is effected in accordance with variations in the resistance in the circuit, with consequent variations in the impedance of the coil, which compensate for said variations in the resistance.

My improvements comprise means to suspend one or the other of the relatively movable solenoid or core elements, so that the weight of the movable mass shall be opposed to the magnetic stress in the solenoid in accordance with the laws controlling the movement of a pendulum, with the result that a characteristic curve indicating the gravitational force acting on the pendulous mass shall substantially coincide with a characteristic curve indicating the magnetic stress in the solenoid throughout the range of movement for which the regulator is designed.

My invention also comprehends the various novel features of construction and arrangement hereinafter more definitely specified and claimed.

As a typical embodiment of my invention I have shown a regulator wherein the core is stationary and the solenoid swings as a pendulum, said solenoid being included in an alternating-current circuit, with arc-lamps arranged in series, so as to maintain the current substantially constant in said circuit regardless of variation in the resistance of the circuit consequent upon variation in the number of said lamps in operation. It is to be understood, however, that I do not desire to restrict my invention to such an embodiment.

In said drawings, Figure I is a side elevation of a regulator with a diagrammatic indication of the circuit in which it is comprised. Fig. II is a plan view of said regulator.

In said figures, 1 is the frame, provided with the standards 2 and 3. Said standard 2 supports the fulcrum 4 of the pendulum 6, which is arranged to swing toward and away from the core 8, fixed upon the top of the standard 3. Said core 8 is conveniently formed of a plurality of U-shaped sheet-iron plates, whose free extremities 9 register with openings in the respective solenoid-coils 10, which latter are carried by the pendulum 6, to which they are conveniently secured by the straps 11 and bolts 12, with their axes at right angles to the length of said pendulum. Said solenoid-coils are connected in series relation in the electric circuit 13, comprising the source of current 14 and the arc-lamps 15.

The relation between the core 8 and the center of gravity of the mass carried by the pendulum 6 is such that under normal conditions the pendulum hangs in the substantially vertical position shown in Fig. I while all the lamps of the series in circuit are in operation. When, however, the resistance of the circuit is diminished by the cutting out of one or more of said lamps, the magnetic stress in the solenoid-coils 10 is correspondingly increased and the latter swing the pendulum toward the core 8, as indicated in dotted lines in Fig. I, with the result that the impedance effect of said coils upon the current is increased to compensate for the decrease in resistance in the circuit, and the current through the remaining lamps is maintained substantially constant.

It is to be understood, of course, that the resistance of the pendulous mass to the magnetic force tending to swing it is increased in definite relation with the increase of the length between the center of gravity of said mass and the center upon which it oscillates, so that by adjustment of said length the regulator may be precisely calibrated to balance

the magnetic stress in the solenoid produced by a given current in the circuit. Such variation in the location of said center of gravity may be secured by providing the pendulum 5 with a movable weight. Therefore the lower extremity 18 of said pendulum 6 is preferably screw-threaded, as indicated, and provided with the nut 19, which retains the weight 20 in such relation as to be adjustable toward 10 and away from the center of oscillation 4 to effect a corresponding adjustment of the center of gravity of the movable mass, including the pendulum 6 and the coils carried by it suspended from said center.

15 In the apparatus above described the characteristic curve indicating the gravitational force acting on the pendulous mass is larger than the characteristic curve indicating the magnetic stress in the solenoid, and a closer 20 approximation of the former to the latter may be secured by shortening the length from the center of oscillation to the axis of the solenoid. However, such alteration in the relative position of the parts would necessitate 25 a greater departure of the solenoid from the axial line of the core during its oscillation, and for convenience of construction a greater radius is preferable.

It is to be understood that I do not desire 30 to limit myself to the precise construction and proportion of the parts which I have illustrated, as it is obvious that various modifications may be made therein without departing from the essential features of my invention.

35 I claim—
 1. In a reactance-regulator for an alternating-current circuit, the combination with a core; of a tubular coil included in the circuit 40 to be regulated and adapted to inclose more or less of said core within it, in accordance with variations in the magnetic stress between said core and coil; and, a pendulum supporting said coil so that the weight of the latter is opposed to the magnetic stress which 45 effects its movement, substantially as set forth.

2. In a reactance-regulator for an alternating-current circuit, the combination with a 50 **U**-shaped core; of a pair of tubular coils included in series in the circuit to be regulated and adapted to respectively and simultaneously inclose more or less of the two free ends of said core within them, in accordance 55 with variations in the magnetic stress between said core and coil; and, a pendulum supporting said coils so that the weight of the latter is opposed to the magnetic stress which effects their movement, substantially 60 as set forth.

3. In a reactance-regulator for an alternating-current circuit, the combination with a frame provided with a standard; of a pendulum mounted to oscillate on said standard; 65 two tubular coils rigidly mounted on said

pendulum parallel with each other, and connected in series with the circuit which is to be regulated; and, a **U**-shaped core mounted on said frame to enter both of said coils simultaneously, in accordance with the movement of said pendulum in response to variations in the magnetic stress between said coils and core, substantially as set forth. 70

4. In a reactance-regulator for an alternating-current circuit, the combination with a frame; of a core mounted upon said frame in acute angular relation therewith; a tubular coil included in the circuit to be regulated and adapted to inclose more or less of said core within it, in accordance with variations 80 in the magnetic stress between said core and coil; and, a pendulum supporting said coil, in registry with said core, so that the weight of the coil is opposed to the magnetic stress which effects its movement, substantially as 85 set forth.

5. In a reactance-regulator for an alternating-current circuit, the combination with a core; of a tubular coil included in the circuit to be regulated and adapted to inclose more or less of said core within it, in accordance 90 with variations in the magnetic stress between said coil and core; a pendulum supporting said coil so that the weight of the latter is opposed to the magnetic stress which 95 effects its movement; and, means to adjustably shift the center of gravity of the mass carried by said pendulum, substantially as set forth.

6. In a reactance-regulator for an alternating-current circuit, the combination with a core; of a tubular coil included in the circuit to be regulated and adapted to inclose more or less of said core within it, in accordance 105 with variations in the magnetic stress between said core and coil; a pendulum supporting said coil so that the weight of the latter is opposed to the magnetic stress which effects its movement; an adjustable weight carried by 110 said pendulum in rigid relation with said pendulum and said coil, upon the same side of the center of oscillation as said coil; and, means to adjust said weight toward and away from the center of oscillation of said pendulum to shift the center of gravity of the mass 115 carried by said pendulum, substantially as set forth.

7. In a reactance-regulator for an alternating-current circuit, the combination with a frame 1; of a standard 2, rigidly mounted on said frame, and provided with a bearing for a fulcrum 4; a pendulum 6, supported by said standard to oscillate upon said fulcrum 4; tubular solenoid-coils 10, mounted parallel with each other in rigid relation with said pendulum 6, and connected in series with the circuit which is to be regulated; straps 11, and bolts 12, securing said coils to said pendulum; a standard 3, mounted upon said frame 1; a **U**-shaped core 8, rigidly supported by 130

said standard 3, to enter said coils 10, in accordance with the oscillation of said pendulum; a weight 20, carried by said pendulum below said coils 10; and, means to adjustably 5 shift said weight toward and away from the center of oscillation 4, substantially as set forth.

In testimony whereof I have hereunto signed my name, at Philadelphia, Pennsylvania, this 9th day of December, 1901.

THOMAS SPENCER.
